UNITED STATES PATENT OFFICE.

EDWIN HUGH AHARA, OF MISHAWAKA, INDIANA, ASSIGNOR TO DODGE MANUFACTURING COMPANY, OF MISHAWAKA, INDIANA, A CORPORATION OF INDIANA.

SHEET-METAL HANGER.

Application filed February 5, 1920, Serial No. 356,439. Renewed September 8, 1923. Serial No. 570,382.

To all whom it may concern:

Be it known that EDWIN HUGH AHARA, citizen of the United States, residing at Mishawaka, in the county of St. Joseph and State of Indiana, has invented certain new and useful Improvements in Sheet-Metal Hangers, of which the following is a specification.

My invention relates to improvements in sheet metal hangers and it more especially consists of the features pointed out in the annexed claims.

The purpose of my invention is to provide a light-weight hanger that is very strong; that consists of few parts; that lends itself to economic and rapid production; and that will successfully meet the practical conditions of the most exacting service.

With these and other ends in view I illustrate in the accompanying drawings such instances of adaptation as will disclose the broad underlying features without limiting myself to the exact details shown.

Fig. 1 Sheet 1 is a side elevation of a hanger with parts broken away and other parts in section.

Fig. 2 Sheet 2 is a side elevation of a detached one-half of a hanger blank.

Fig. 3 Sheet 2 is an edge elevation of Fig. 2 partly in section on line $\alpha\alpha$ of Fig. 2.

Fig. 4 Sheet 2 is a transverse section on line $m\bar{m}$ of Fig. 2.

Fig. 5 Sheet 3 is a view similar to Fig. 3 with two halves in their assembled relation.

Fig. 6 Sheet 3 is a top plan view of the sides of a hanger, without the feet being attached thereto.

Fig. 7 Sheet 3 is a transverse section in plan on the line $y\bar{y}$ of Fig. 1.

Fig. 8 Sheet 1 is an elevation in transverse section of one of the hanger feet on line $o\bar{o}$ of Fig. 1.

Fig. 9 Sheet 1 is a skeletonized perspective of the reinforcements contained in the hanger feet.

Fig. 10 Sheet 3 is a plan view of a hanger foot with its supporting surface removed.

Fig. 11 Sheet 3 is a section of Fig. 10 on the line $a\bar{a}$.

Fig. 12 Sheet 1 is a detached perspective of a stamped up cross "bar" forming the under support of the shaft bearing.

Fig. 13 Sheet 1 is a cross section centrally located of Fig. 12.

Fig. 14 Sheet 1 is a detached perspective of a beveled angle plate.

Fig. 15 Sheet 1 is an end elevation of a square recessed nut.

Fig. 16 Sheet 3 instances alternatives A, B and C as substantial equivalents of full depth flanges formed on both halves of a hanger body.

In carrying my invention into practice, economy and rapidity of production is provided for by making the two halves of a hanger body, substantially duplicates of each other and assembling them in coordinate relation to each other so that an open hollow interior is secured and coating parts are formed adjacent each other on opposite sides of the hollow interior.

This is done by taking a Sheet 1 and blanking it approximately as shown in Fig. 2, Sheet 2 by means of dotted lines. Flanges 2 are shown in full lines. These occur along the main hanger edges. The body members are wider at one end than the other. At the narrow end a slot is formed between two forks 5. The inner flanges of the forks are indicated by 3 and a transverse flange 4 almost spans the width of the slot 7. An opening 6 is formed above the slot 7, leaving a cross piece 41 which separates the one from the other. Flanges 8 project from the edges of opening 6.

The widest portion of the body 1 is provided with feet 29. This end of the body may be uppermost, when used as a hanger, or lowermost, when used as a "pedestal" bearing support. It is quite immaterial in what position the hanger is placed, vertical or in an angular relation to these. The feet 29 have a flat portion 9 against which the usual lag screws or fastening bolts 35 abut. The feet 29 are provided with internal reinforcements 30 and 34 shown in Fig. 9. The reinforcement 30 passes around the fastening bolts 35 and by means of projections 31 is secured by spot welding, or otherwise to the body parts 1. On each side of the "loop" 30 lateral reinforcements 34 are placed. These fill the space, edge-wise, between the bearing part of the feet and the cover portion 9 both of which extend laterally on each side of the body to give width to the feet. There are projections from the part 9 which engage the body 1 and flanges 2. The projections 33 engage the flanges 2 and projections 32

engage the body on its front and rear. All these parts are welded or otherwise secured to each other preferably the former so as to make a substantially internal structure having a hollow interior. The holes 36 accommodate bolts 35. The main foot portions are bent up from a single flat piece of sheet steel by various blanking and forming operations so as to make a very light, strong and rigid structure.

The fork parts 5 that project on each side of the slot 7 are provided with slotted holes 10 that accommodate horizontal set screws 15 formed in the outer flanges 2 and the inner flanges 3. Between these flanges square distance nuts 17 having a threaded opening and a recess 18, are placed. The set screws 15 pass through these nuts so that the inner ends engage opposite sides of the bearing 13 of shaft 37, thus making it possible to adjust the shaft on the plane of these set screws and when so adjusted lock nuts 16 hold the set screws against accidental or other unintended displacement. A similar nut 17 is placed adjacent the cross piece 41 and between flanges 4 and 8 to receive set screws 14. Slots 11 and 12 in these flanges permit of lateral adjustment and the set screw 14 locked by nut 16 determines the vertical position of the bearing 13 and also of the set screws 15 which pass through slots 10.

The open end of the slot 7 is closed by a stamped-up bar 19 shown in Fig. 12 Sheet 35. 1. It has holes 20 at each end for bolts 22 that pass through holes 20' of the forks 5. This arrangement permits the easy placement of a shaft 37 without "threading" the hangers over a long shaft. A nut 17 is placed inside of the bar 19 between its lower wall 24, upper wall 26 and side walls 23. A set screw 14 passes through this nut and slots 21 formed in the upper and lower parts 26 and 24 respectively of the bar 19. The ends of the upper part 26 are cut away at 27 to accommodate the forks 5. This bar is also formed with a single piece of flat metal, thus making a very strong, yet light structure. It is bevelled off at 25 to eliminate sharp corners and the forks are bevelled accordingly. This leaves an opening at the lower end of the forks which is closed by the insertion of beveled angle plates 28 shown in Fig. 14 Sheet 1.

It will be seen that the duplicate halves 1 with the respective flanges are simply assembled so that the companion flanges overlap each other. They are so held by spot or continuous welding or in any other way to form a structurally integral unit of great strength. It is however plain that certain modifications may be used, instead of the flanges 2. Some of these alternatives are shown in Fig. 16 wherein at A a distance strip 39 is instanced which may be welded

edgewise to the body parts 1. At B a separator 38 with flanges serves to hold the parts 1 the intended distance apart. At C the short flanges 40 of the parts 1 abut each other and a distance piece 39 overlaps these flanges, on the inside or outside (not shown) so as to hold the parts together through electric welding or otherwise. In any event great economies in production are secured by making the body parts in duplicate. Should the alternative shown at C of Fig. 16 be used or either of the other substitutes, not all of the flanges 2 would need to be replaced. Freedom of selection would determine the relation the respective forms should bear to each other.

In Fig. 1 a foot is shown in dotted lines at the left hand side. This is not a modification but an adaption of the same type of feet for shorter hangers. Other positions may be selected for still shorter types. Likewise the dotted shaft lines of this same figure show variations in position of the shaft 37.

It is to be understood that the use of rivets etc., to hold duplicate parts together instead of welding the same comes within the scope of my present invention which in its broadest sense comprises the grouping of duplicate halves to form a hollow hanger structure regardless of the specific contours, shapes, etc., that the various parts may assume.

What I claim is:

1. In sheet metal hangers, stamped-up 100 duplicate halves provided with edgewise flanges, and means for holding them assembled with the flanges of one half overlapping those of the other half in alternative inside and external relation.

2. In sheet metal hangers, stamped duplicate halves having edgewise flanges, means for assembling the halves with the flanges of the two halves engaging each other in alternative inside and outside relation, and means for holding the parts in engagement to form a hollow box-like structure.

3. In sheet metal hangers, duplicate halves provided with projecting flanges at some of the edges thereof, means for assembling the halves with coacting flanges in face to face contact with each other in alternative inside and outside relation, and means for holding the assembled parts in rigid relation to each other.

4. In sheet metal hangers, duplicate body parts having a portion of their edges provided with projecting flanges adapted to be assembled with the flanges in a side-by-side alternative internal and external relation, suitable feet secured to the body parts at one end thereof, and bearing supporting members secured to the other end of the body parts to form a hollow reinforced shaft supporting structure.

5. In shaft hangers, duplicate sheet metal body parts formed with flanges which project from a portion of the edges of each body part and adapted to cooperate with each other in alternative inside and outside relation, said body parts having a shaft bearing opening at one end thereof, suitable feet at the other end, and removable means for closing the said opening after a shaft bearing is in position therein and adapted to be opened to also admit placing the shaft bearing into position in the opening or removing the same therefrom.

10. In shaft hangers, duplicate sheet metal parts having alternatively positioned flanges constituting the body portion of a complete hanger, a shaft opening at one end, a stamped removable closure member for such opening, widened-out stamped feet attached to the other end of the body parts, and means for holding all the parts in assembled relation.

15. In shaft hangers, a sheet metal body portion composed of duplicate stampings,

formed wider at one end than the other, a 25 slotted opening at the narrow end, an isolated opening adjacent the slotted opening, a removable stamped closure for the extreme termination of the slotted opening, separate pressed sheet metal feet at the wide end of the body, internal reinforcements for said feet, flanged edges of said body portions adapted to be assembled so that the flanges of one half of a body portion overlap the flanges of the other half of the body, and 30 means for holding the body and feet in substantially integral assembled relation.

35. In shaft hangers, a hanger body formed by two flanged principal sheet metal members so as to enclose a hollow rectangular interior, and means for holding such members in assembled relation with the flanges of one half in alternative inside and outside position with respect to the flanges of the other half.

40. In testimony whereof I affix my signature.

EDWIN HUGH AHARA.
